UNITED STATES PATENT OFFICE

SERN MADSEN, OF CLINTON, IOWA, ASSIGNOR TO CURTIS COMPANIES, INCORPORATED
OF CLINTON, IOWA, A CORPORATION OF IOWA

SASH BALANCE AND WEATHER STRIP STRUCTURE

Application filed June 29, 1931. Serial No. 547,612.

The object of my present invention is to provide a novel and inexpensive and effective spring sash balance and method of connecting the same with a window sash and window frame.

In this connection, it is my purpose to provide a means for connecting the spring balance with the sash and frame in such a way as to facilitate the convenient and inexpensive and simple assembling and installing of the parts.

Another purpose is to provide a means for assembling a spring balance in connection with a window frame for quickly adjusting the connections for springs of different lengths.

Another purpose is to provide a weatherstrip structure of very simple construction which may be inexpensively installed.

Another purpose is to provide such a weatherstrip arrangement by which there is afforded a double weatherseal and a guide for holding the sash in proper adjustment.

Another purpose is to provide a weatherstrip construction of peculiar shape and having novel means for holding the weatherstrip elements in place.

Still a further object is to provide the combination of a weatherstrip structure and sash balance spring and means for installing the sash balance spring.

With these and other objects in view, my invention consists in the construction, arrangement and combination of the various parts of my sash balance and weatherstrip structure, whereby the objects contemplated are attained, as hereinafter more fully set forth, pointed out in my claims, and illustrated in the accompanying drawings, in which:

Figure 1 is a perspective view partly in section of a part of a frame and sash equipped with a weatherstrip embodying my invention.

Figure 2 is a perspective view of one of the weatherstrip elements.

Figure 3 is a detail, sectional view taken on the line 3—3 of Figure 1.

Figure 4 is a vertical, sectional view illus-

trating the manner of installing the spring sash balance.

Figure 5 is a perspective view of a modified form of a member which serves to hold the weatherstrip in place and likewise as an anchoring means for one end of the spring.

Figure 6 is a horizontal sectional view through a window frame and part of a double hung sash assembled in connection therewith equipped with a slightly modified form of weatherstrip embodying my invention.

Figure 7 is a vertical, sectional view taken on the line 7—7 of Figure 6; and

Figure 8 is a perspective view of a weatherstrip unit including the members for engaging the ends thereof and holding it in place.

In the accompanying drawings, I have used the reference numeral 10 to indicate generally the side jamb of a window frame having the parting stop 11.

In Figure 6, I have shown a slightly different form of frame having the side jamb 10a and the parting stop 11a, the blind stop 12 and the inner stop 13.

In Figure 1, I have shown an ordinary sash 14. In Figure 6, I have shown the upper and lower sash 15 and 16.

In Figures 1 to 5 inclusive, I have shown one form of weatherstrip and in Figures 6 to 8 a slightly different form.

Where the form of weatherstrip shown in Figures 1 to 5 is used, I provide the stiles and the ends of the rail of the sash 14 with a vertical groove 17 (see Figure 3) and a spring groove 17a.

I provide a weatherstrip unit or section indicated at A and comprised preferably of a single sheet of somewhat resilient sheet metal folded along a vertical central line to form a rather narrow U-shaped portion 18, the walls of which converge as shown, at 19, whence they curve substantially away from each other and then are shaped to form two opposite channel-shaped or concave portions 20 with the open slot or mouth 21 of substantial width.

I might for convenience call the parts of the weatherstrip unit on opposite sides of 106

the contracted neck portion 19, part A¹ and part A². In the installation, the greater portion of the part A¹ is inserted into the vertical slot 17, while the portion A² and perhaps some of the portion A¹ projects into a vertical groove 22 in the side jamb 10. The groove 22 may or may not be provided with a metal lining 23. The resilience of the weatherstrip unit is such that the leaves 10 or members 20 resiliently engage and press against the walls of the groove 22 or the lining as the case may be.

The portion A¹ may fit rather snugly into the slot 17 but it is preferably to provide 15 some means for insuring the proper holding of the unit in place against vertical sliding movement with relation to the window sash.

For this purpose, I have provided the U-shaped staple 24 having the pointed arm, 20 24a preferably barbed adapted to be driven into the bottom rail of the sash and having also the smooth arm 24b adapted to project upwardly into the portion A¹ as best shown in Figure 3.

25 At the top of the weatherstrip unit, a plate 25 is inset in the upper surface of the top rail of the sash and projects over the upper end of the weatherstrip unit. The plate 25 has a pin or the like 26 extending 30 downwardly into the portion A¹. (Figure 3.)

I will now refer to the form of the device illustrated in Figures 6 to 8 inclusive.

In these figures, the jamb 10a is shown 35 provided with an upright groove 34 for each sash. The groove 34 may be provided with a metal lining 35 similar to the lining 23 if desired. Each sash is provided with a corresponding aligned upright groove 36.

40 I use a weatherstrip unit B similar in shape to the unit A, except it is substantially wider so as to afford a housing in whole or in part for the spring 37. For holding the unit B in place, I have provided slightly 45 different means from that already described. At the top there is provided a plate 38 attached to and preferably countersunk in the top of the sash and having a portion which overhangs the groove 36 and terminates in a down-turned curved plate-like 50 portion 39. (See Figures 7 and 8.) The portion 39 projects into and fits snugly against the wall of the weatherstrip unit B.

At the lower end of the weatherstrip unit, 55 I provide a similar plate 40 having a similar portion 41, which is up-turned and projects into the lower end of the weatherstrip unit.

The plate 40 has horizontal projecting 60 spaced parts 42 between which is formed the hook 43 to which the lower end of the spring 37 may be fastened as shown for instance in Figure 7. The spring is then partially housed within the weatherstrip unit B.

65 In Figure 4, I have shown a slightly dif-

ferent manner of installing the spring in place. For instance, I have shown at the upper end of the spring a series of holes 44 in the jamb 10a. A screw or the like 45 may be placed selectively in one of the holes for thus arranging the upper end of the spring at the height suitable for the particular sash which is being hung. At the lower end of the spring instead of the member 40 already described, there may be used the member 46 having the up-turned pin or the like 47 fastened into the lower end of the sash. The part 46 has an up-turned member 48 similar to the member 41 received within the lower end of the weatherstrip unit. Secured to the part 46 is also a hook 49 for the lower end of the spring 37.

It will thus be seen that I have provided a weatherstrip and sash balance structure having a number of advantages.

When the parts are all installed, the sash may have lateral play or as it were a sort of floating movement, and yet there will be formed a double weatherseal made by the engagement of the resilient spaced side members of the weatherstrip unit with the walls of the groove in the jamb or the lining thereof.

I have shown a simple and inexpensive means for holding the weatherstrip units in their grooves. This means includes a simple anchoring element with a member projecting within the channel of the weatherstrip.

There is also disclosed means for both holding the weatherstrip in place and anchoring the spring.

In either form disclosed, the groove in the sash may be shaped to fit the weatherstrip and the latter so made as to engage the walls of the sash grooves under tension. This would have several advantages. In installation, the weatherstrip units would remain in place after insertion until the holding means had been also installed. The weatherstrip would have a snug fit in the sash, thus avoiding sliding toward or from the frame.

There is an advantage in supporting the weatherstrip on the sash and making it the length of the sash and projecting it into the jamb, because the weatherstrip can then be conveniently inserted into position or removed for repairs or replacement.

There are several advantages in assembling the spring in the manner herein disclosed by fastening it to the bottom of the sash and to the jamb. With this arrangement, the spring can be inserted or removed without the necessity for removing any of the parts of the window frame. For instance, a string can be fastened to the upper end of the spring and the spring can be dropped down between the sash and the jamb until its lower end projects below the

sash. It can thereupon be hooked in place and the upper end pulled upwardly by means of the string and fastened to the appropriate screw 45.

5 With this arrangement, access to the upper end of the spring is easy and convenient. The point where the upper end of the spring is anchored on the jamb may be quickly and easily varied to suit the conditions of the installation. It is obvious that changes may be made in the details of the structure and arrangement of parts of my device as here shown, and it is, of course, my purpose to cover by my claims any modified forms of structure or use of mechanical equivalents, which may be reasonably included within their scope.

I claim as my invention:

1. In a structure of the kind described, 20 the combination of a frame having grooves and a sash slidable therein having aligned grooves, with weatherstrip units substantially channel-shaped, each having a portion received in one of said sash grooves and a 25 portion projecting into one of said frame grooves, retaining elements attached to the sash above and below the weatherstrip having parts projecting into the ends of said channel shaped weatherstrip for holding the 30 weather strip in its groove in the sash.

2. In a structure of the kind described, 35 the combination of a frame having grooves and a sash slidable therein having aligned grooves, with weatherstrip units substantially channel-shaped, each having a portion received in one of said sash grooves and a portion projecting into one of said frame 40 grooves and with converging walls between said portions, plates inset in the sash above and below the weatherstrip units having parts with members projecting into the ends of said weatherstrip units, said last-described portions of the plates being curved to fit the wall of the weatherstrip.

45 3. In a structure of the class described, the combination of a frame having grooves and a sliding sash having aligned grooves, with channel-shaped weatherstrip units, each secured in a sash groove and having 50 spaced spring leaves projecting into a frame groove and forming weatherseals at the sides thereof, a retaining element fixed at the top of each weatherstrip unit having a port projected into the weatherstrip, and a 55 staple member having a member secured to the bottom of the sash and a member projecting into the lower end of each weatherstrip unit.

4. In a structure of the class described, 60 the combination of a frame having grooves and a sliding sash having aligned grooves with channel-shaped weatherstrip units, each secured in a sash groove and having spaced spring leaves projecting into a frame 65 groove and forming weatherseals at the

sides thereof, means for holding the weatherstrip units in place to slide with the sash, and sash balance means substantially housed in the weatherstrip units.

5. In a structure of the class described, 70 the combination of a frame having grooves and a sliding sash having aligned grooves with channel-shaped weatherstrip units, each secured in a sash groove and having spaced spring leaves projecting into a frame 75 groove forming weatherseals at the sides thereof, means for holding the weatherstrip units in place to slide with the sash, and sash balance means substantially housed in the weatherstrip units, each having one end 80 secured to the sash, and means for securing the other end of said means to the jamb at various heights on the jamb.

6. In a structure of the class described, 85 a channel-shaped weatherstrip unit having its walls slightly converging between its closed and its open side, and a weatherstrip holding means comprising a plate having a member adapted for insertion into the end of the weatherstrip.

7. In a structure of the class described, 90 a channel-shaped weatherstrip unit having its walls slightly converging between its closed and its open side, and a weatherstrip holding means comprising a plate having a member adapted for insertion into the end of the weatherstrip, said plate having a curved tongue to which a counterbalance spring may be fastened.

8. In a structure of the class described, 100 the combination of a channel-shaped weatherstrip having spaced spring leaves at its open side, and having its walls slightly converging between its open and its closed side, with a holding means comprising a 105 member adapted to extend across the edge of the strip at one end, a portion adapted to be inserted into the end of the weatherstrip, and a portion adapted to be inserted into one end of a window sash.

9. In a structure of the kind described, 110 the combination of a frame having grooves and a sash slidable therein having aligned grooves, with weatherstrip units substantially channel-shaped, each having a portion received in one of said sash grooves and a portion projecting into one of said frame grooves, and plates inset in the sash above and below the weatherstrip having parts with members projecting into the ends of 115 said weatherstrip.

10. In a structure of the class described, 120 the combination of a frame having grooves with a sash slidable therein and weatherstrip units, each secured to and adapted to slide with the sash, and having spaced spring leaves projecting into a frame groove and forming weatherseals at both sides thereof.

11. In a structure of the kind described, 125

- the combination of a frame having grooves and a sash slidable therein having aligned grooves with rounded bottoms, with weatherstrip units substantially channel-shaped, 5 each having a portion correspondingly shaped and snugly received in one of said sash grooves and a portion projecting into one of said frame grooves and yieldingly engaging the opposite walls thereof.
- 10 12. In a window construction, the combination of a frame having opposite lengthwise grooves, with a sash slidably received in the frame, weatherstrip units on the sash, having spaced leaves projecting into said grooves and yieldingly engaging the opposite walls thereof, and sash balance means partially housed in the weatherstrip units.
13. In a window construction, the combination of a frame having opposite lengthwise grooves, with a sash slidably received in the frame, weatherstrip units on the sash, having spaced leaves projecting into said grooves and yieldingly engaging the opposite walls thereof, sash balance means secured to the sash and to the frames and partially housed in the weatherstrip units, and devices for engaging the bottom of the sash and serving the double function of holding the weatherstrips in place and serving as anchors for the sash balance means.
14. In a structure of the kind described, the combination of a frame having grooves and a sash slidable therein having aligned grooves, with weatherstrip units substantially channel-shaped, each having a portion received in one of said sash grooves, and a portion projecting into one of said frame grooves and with converging walls between said portions, means for holding the weatherstrip in place to slide with the sash, and means for counterbalancing the sash.
15. In a structure of the kind described, the combination of a frame having grooves and a sash slidable therein having aligned grooves, with weatherstrip units substantially channel-shaped, each having a portion received in one of said sash grooves and a portion projecting into one of said frame grooves, and plates inset in the sash above and below the weatherstrip having parts with members projecting into the ends of said weatherstrip, and means for counterbalancing the sash.
16. The combination of a frame element and a sash element slidable therein with members forming weatherstrips and guide means between the sash and frame, each 60 rockingly mounted on the sash and having spaced resilient leaves arranged to engage spaced faces of the frame.
17. The combination of a frame element and a sash element slidable therein with a 65 pair of weatherstrip and guide members, each associated with one of said elements to rock thereon and having spaced resilient leaves frictionally engaging spaced vertical surfaces of the other of said elements.
18. The combination of a frame element 70 and a sash element slidable therein, one of said elements having vertical grooves in its sides, a substantially U-shaped weatherstrip member associated with the other of said elements to rock thereon horizontally but non-movable lengthwise thereof, and having resilient leaves projected into said grooves and diverging and frictionally engaging the sides thereof.
19. The combination of a frame having 80 vertical grooves in its sides and a sash vertically slidable in the frame with weatherstrip members associated with each side of the sash to slide therewith and rock thereon, each having spaced leaves projected into one 85 of said grooves for frictionally engaging the sides thereof in any vertical or longitudinal adjustment of the sash for forming a weatherseal, substantially the length of the sash.
20. The combination of a frame and a 90 sash slidable therein, provided with vertical grooves in its side stiles, a weatherstrip member for each side of the sash substantially coextensive in length therewith adapted to be installed by insertion lengthwise into the 95 groove of the sash, each said weatherstrip element having a rocking connection with the sash and having spaced resilient leaves frictionally engaging with spaced faces of the frame.
